United States Patent Office

Des. 222,842

Patented Jan. 11, 1972

222,842

WASTE RECEPTACLE OR SIMILAR ARTICLE

Walter J. Merck, Old Brookville, and Howard E. Thompson, Huntington, N.Y., assignors to Lunn Laminates, Inc., Wyandanch, N.Y.

Filed June 3, 1970, Ser. No. 23,290

Term of patent 14 years

Int. Cl. D7—05

U.S. Cl. D49—30

FIG. 1

FIG. 2

FIG. 3

FIG. 4

FIG. 5

FIG. 1 is a top plan view of a waste receptacle or similar article showing our new design;

FIG. 2 is a front elevational view;

FIG. 3 is a bottom plan view;

FIG. 4 is an elevational view looking from the right of FIG. 2; and

FIG. 5 is a rear elevational view thereof.

The side opposite that shown in FIG. 4 is a mirror image of the side shown.

We claim:

The ornamental design for a waste receptacle or similar article, substantially as shown and described.
